FENDER FOR AN AUTOMOBILE

James H. Sipple, Royal Oak, Mich., assignor to General Motors Corporation, Detroit, Mich., a corporation of Delaware

Application December 16, 1954, Serial No. 33,584

Term of patent 7 years

(Cl. D14—6)

Figure 1 is a side elevational view of a fender for an automobile, showing my new design;

Figure 2 is a top plan view of the fender;

Figure 3 is a sectional view taken on the plane indicated by line 3—3 in Figure 1;

Figure 4 is a sectional view taken on the plane indicated by line 4—4 in Figure 1;

Figure 5 is a sectional view taken on the plane indicated by line 5—5 in Figure 1; and

Figure 6 is an end elevational view of the fender.

The fragmentary portions of the automobile shown in broken lines are disclosed only for illustrative purposes.

I claim:

The ornamental design for a fender for an automobile, substantially as shown and described.
